UNITED STATES PATENT OFFICE.

EDGAR M. BENHAM, OF NORWOOD, OHIO, ASSIGNOR TO THE MOSLER LOCK COMPANY,
OF COVINGTON, KENTUCKY, A CORPORATION OF OHIO.

LOCK.

Application filed June 12, 1926. Serial No. 115,440.

This invention relates to locks, and more particularly relates to locks of the type which are customarily used in connection with safety deposit lock boxes, and to an anti-pick device adapted to be associated with locks of this character.

One favorite type of locks for safety deposit lock boxes is provided with an aperture in the cover plate, which is in alignment with a stump carried by the bolt bar, the ends of the tumblers of the lock being adjacent to this stump. When the lock is dismounted from the door of the safety deposit box, the aperture referred to gives access to the tumblers, by means of an instrument or tool, and permits the tumblers being aligned in this way with the stump, so that the bolt bar may be retracted. This gives an opportunity to an unauthorized person to tamper with the lock in such a way that it will not give protection to the extent desired.

The principal object of my invention is to provide a lock of the character described, which frustrates attempts by unauthorized persons to align the tumblers with the locking stump, by manipulation through the aperture in the cover plate at the top of the stump, and thus to secure added protection.

A further object of my invention is to provide a simple and inexpensive device adapted to be associated with locks of various types and different constructions, for preventing access to the tumblers through the stump aperture in the cover plate of the lock. A further object of my invention is to provide a device of the character described, which may be applied to locks of various types and different constructions, without requiring changing or altering any part of the lock, but merely by adding the device thereto. Other objects of my invention will be in part obvious and in part pointed out hereinafter.

In order that a clearer understanding of my invention may be had, attention is hereby directed to the accompanying drawings, forming a part of this application and illustrating one possible embodiment of my invention.

Referring to the drawings, Fig. 1 is a top elevation of a lock, to which an anti-pick

device embodying my invention has been applied; Fig. 2 is a side view thereof, partly broken away and partly shown in section; and Fig. 3 is a perspective view of the anti-pick device.

Similar reference characters refer to similar parts throughout the several views of the drawings.

Referring to the drawings, the anti-pick device comprises a flat piece 1, of metal or other suitable material, provided with an aperture 2, conforming to the size and shape of the transverse dimensions of the locking stump 3 of the lock. This plate 1 is placed between the cover plate 4 of the lock and the tumblers 5, with the upper end of the locking stump projecting through the aperture 2. The plate 1 is large enough to close the aperture 6 in the cover plate intermediate the locking stump and the tumblers, during all positions of the locking stump, so that access can at no time be had to the tumblers 5 through the aperture 6. It will be readily apparent that the plate 1 positively prevents the picking of the tumblers 5 through the aperture 6 when the lock is dismounted from a door, or the like.

To apply the anti-pick device, it is merely necessary to remove the cover plate 4 of the lock, put the anti-pick device 1 in place, and replace the cover plate. In the construction illustrated, the cover plate is secured in place by means of a screw 7.

What I claim is:

The combination with a lock, including a housing, a locking stump movable in the housing, tumblers in the housing having their front ends adjacent and recessed for the locking stump, and a cover plate having an aperture opposite the outer end of the locking stump, of a plate engaging the locking stump for movement therewith disposed intermediate the cover plate and the tumblers and extending across said aperture in all positions of the locking stump, whereby access to the ends of said tumblers adjacent the locking stump through said aperture is prevented.

This specification signed this 7th day of June, 1926.

EDGAR M. BENHAM.
